UNITED STATES PATENT OFFICE

TENIS HOFFMAN, OF NOBLEFORD, ALBERTA, CANADA

CLAMP FOR BATTERY TERMINAL POSTS

Application filed August 12, 1929. Serial No. 385,414.

This invention relates to improvements in clamps for battery terminal posts and the object of the invention is to devise an improved form of clamp for detachably connecting a cable to a battery terminal post which, while being extremely secure and giving a good contact, may be very readily detached and removed from the post and which will be of simple and inexpensive construction.

The invention consists in the construction and arrangement of parts, all as herein-after more particularly described, and illustrated in the accompanying drawings in which,

Figure 1 shows a perspective view of one form of the improved clamp connected to a battery terminal post.

Figure 2 is a top plan view in closed or gripping position.

Figure 3 is a horizontal longitudinal section through the clamp also in closed position.

Figure 4 is a top plan view of a slightly modified form in which the clamp may be made.

In the drawings like characters of reference indicate corresponding parts in the different views.

In the drawings the casing of the storage battery is indicated by the numeral 10 and the terminal post by the numeral 11.

The improved clamp is indicated collectively by the numeral 12 and in the form shown in Figures 1, 2 and 3 comprises a body portion 13 which is formed with a shank 14 having a recess 15 therein into which the end of a cable 16 is adapted to be secured for connection to the clamp.

The body portion 13 also comprises a half jaw portion 17 which is in the form of an arc of a circle. The body portion 13 is also formed with bifurcated lugs 18 at the inner end of the jaw portion 17.

Associated with the half jaw portion 17 is a companion half jaw portion 19 the inner portion of which is in the form of an arc of a circle and this half jaw portion 19 is hingedly connected at one end between the

lugs 18 of the half jaw portion 17 by means of a pin 20.

The half jaw portions 17 and 19 are adapted to be closed together, as illustrated, and when so closed the inner arcuate portions thereof form between them a circular opening 21 adapted to receive the terminal post 11.

Swingably connected to the half jaw portion 19 is a loop 22 one end of this loop being connected to the half jaw portion 19. This loop is adapted to swing over the end of the half jaw portion 17 when the jaw portions are closed and the free end of the loop carries a cam lever 23 the cam portion 24 of which is adapted to engage within a recess 25 formed in the half jaw portion 17.

Carried by the half jaw portion 19 is a pin 26 which projects into the opening 21 and forms a spicular projection extending into this opening.

In the form shown in Figure 4 the construction is practically the same except that a slightly different disposition of the various parts is employed but the operation is identical with that shown in Figures 1, 2 and 3.

In attaching the clamp to the terminal post it is merely necessary to separate the half jaw portions 17 and 19 by swinging them about the pin 20 and closing them upon the terminal post 11 after which the loop 22 is swung over the end of the jaw portion 17 and by closing the cam lever 23 the jaw portions are drawn together so as to securely grip the terminal post and in this operation the spicular projection 26 will penetrate into the post 11.

In order to remove the clamp it is only necessary to rotate the cam lever 23 which will permit the opening of the jaws and the disengagement of the clamp from the post 11.

The improved clamp is of extremely simple and inexpensive construction and provides a convenient and efficient manner of connecting a cable to a battery terminal post.

A feature of the improved clamp is the manner in which the locking of the two jaw portions into gripping engagement with the

terminal post is effected. It will be noted that this comprises the loop 22 which cooperates with the outer ends of the jaw portions opposite to the hinge connection and serves to securely hold these outer ends in closed position.

A further feature is that all parts of the clamp are positively connected together so that the disengagement of the clamp does not necessitate removal or complete separation of any of the parts from the clamp and thus there is no likelihood of any of the parts being lost but the clamp is at all times a complete unit ready for connection to the battery terminal.

Various modifications may be made in this invention without departing from the spirit thereof or the scope of the claim, and therefore the exact forms shown are to be taken as illustrative only and not in a limiting sense, and it is desired that only such limitations shall be placed thereon as are disclosed in the prior art or are set forth in the accompanying claim.

What I claim as my invention is:—

A clamp for battery terminal posts comprising a body portion formed with means for receiving the end of a cable and with a half jaw, a second half jaw portion hingedly connected at one end thereof to one end of the first half jaw portion, said half jaw portions when in closed position forming therebetween a post receiving opening, an elongated loop swingably connected to the free end of one of the jaw portions and adapted to swing over the other jaw portion, and a cam lever pivotally connected to the free end of said loop, one of the jaw portions formed with a recess adapted to receive said cam lever when the jaws are in closed position, and a spicular projection carried by one of the jaw portions and forming a projection extending into the post receiving opening.

In witness whereof I have hereunto set my hand.

TENIS HOFMAN.
